UNITED STATES PATENT OFFICE.

GEORGE A. MACKENZIE, OF BAY CITY, MICHIGAN.

DOWNDRAFT FURNACE.

Application filed December 9, 1922. Serial No. 605,792.

To all whom it may concern:

Be it known that I, GEORGE A. MACKENZIE, a citizen of the United States of America, and a resident of Bay City, in the county of Bay and State of Michigan, have invented certain new and useful Improvements in Downdraft Furnaces, of which the following is a specification.

This invention relates to downdraft furnaces and the like.

One object of the invention is to construct a furnace which will burn slack, mine run, and other cheap fuels which cannot be satisfactorily burned in other furnaces, due to the soot and dirt given off during combustion. My improved furnace will readily burn fuel of this kind, thereby effecting a material saving in operating cost.

Another object of the invention is to design a downdraft furnace so that the air admitted to the furnace will be pre-heated and assist in consuming the soot and combustible gases given off by the cheaper and poorer grades of fuel.

A still further object of the invention is to construct a furnace having a maximum area of heating surface to the end that all of the heat may be utilized.

A further object still is to design a furnace which will be light in weight, economical to manufacture, and simple and easy to assemble and install.

A still further object is to provide means whereby any smoke and gases which may be accumulated in the fuel magazine may be drawn into the radiator prior to the opening of the fuel magazine door.

The above and other objects will appear as the specification progresses, reference being had to the accompanying drawings, in which I have shown the preferred embodiment of my invention, and in which like reference numerals indicate like parts throughout the several views thereof.

In the drawings:

Fig. 1 is a part sectional vertical view taken on the line 1—1 of Fig. 3.

Fig. 2 is a cross sectional view taken on the line 2—2 of Fig. 1.

Fig. 3 is a part sectional top plan view taken on the line 3—3 of Fig. 1.

Fig. 4 is a side view of the dampers controlling the admission of the ashes to the ash pit, the dampers being shown in two positions, viz, open and closed.

Fig. 5 is an enlarged fragmentary view

illustrating the openings from the air chamber into the fire pot.

Fig. 6 is an enlarged top plan view illustrating the air deflecting lip. 60

Fig. 7 is an enlarged fragmentary front view of the door locking mechanism.

Fig. 8 is a cross sectional view thereof.

In my preferred construction I provide a base 5 which can be of any desired shape, 65 but which I prefer to make cylindrical as shown, this is termed the ash pit into which the ashes are dumped, and this ash pit is provided with an opening 6 through which the ashes are adapted to be removed and 70 which is closed by the door 7 hinged to the base in the usual manner.

A combustion chamber 8 is mounted on this base 5, and this chamber is formed with hot air outlet openings 9 adapted to 75 communicate with suitable pipes or ducts 10, 10^a and 10^b which extend to the radiator at the top of the furnace. Grate supports 11 are provided as shown and can be cast integral with this chamber 8 or bolted 80 thereto as desired, these supports diverge inwardly to detachably support the grate 12 which can be of any approved type, link 13 connecting the grate with the shaker handle 14 for shaking the grate to remove 85 the ashes or clinkers therefrom, this handle being pivotally connected to the furnace in the usual manner. An opening 15 is also provided in the front of this chamber, and a door 16 is provided as a closure therefor. 90

The opening between the combustion chamber 8 and the base 5 is normally closed by a series of dampers 17 rotatably mounted in suitable boxes in the base, and which are positioned in over-lapping relation with 95 each other to prevent air rushing into the combustion chamber when the ash door is opened. One end of the links 17^a are anchored to the respective dampers, the opposite ends of the links being pivotally 100 connected in spaced relation to a bar 18 which extends through the casing and is pivotally connected to a control handle 19 which is in turn pivoted to the outer casing, and this handle 19 is adapted to be actuated 105 to dump the ash accumulated on the dampers into the ash pit, and it will be obvious that the ashes falling from the grate fall on these dampers, and accumulate thereon until such time as the handle 19 is operated to dump 110 them into the ash pit.

A fire pot 20 is mounted on this combus-

tion chamber 8 and is formed with a plurality of air receiving openings 21 arranged in spaced relation in the wall thereof for pre-heating the air drawn into the furnace 5 through the slide damper 22, an annular air belt 23 surrounding these air receiving openings, and having direct communication therewith, and I wish to direct particular attention to the construction of the walls 10 of the fire pot as shown in section in Fig. 3, the distribution and forming of metal making possible the pre-heating of the air, and still retaining the natural radiating properties of the fire pot. This forming of the 15 fire pot for pre-heating the air caused by its flowing down around the walls of the fire pot, is one of the prime elements of my invention, and furnishes oxygen, etc., for burning combustible gas, soot, etc. A small 20 door or poke hole cover 16^a is hingedly connected to the door 16 and is used when it is desired to poke the fire when it is not necessary to open the large door which admits considerable air. The top of this fire pot 20 25 is provided with a flange 20^a in which the flat section 24 is mounted, an upstanding lip 24^a being formed integral with this section as shown in Fig. 6 to break the current of air entering through the hinged damper 30 25. The lower section 26 of the fuel magazine 27 is mounted on the member 24, the lower end of this section being formed with a lateral extension 28 having a downwardly projecting edge 28^a which when in position, 35 forms an air chamber between this section and the flat member 24, air being admitted from the damper 25. The inner lower edge of this fuel magazine is formed with a plurality of spaced apart openings 27^a as clearly 40 shown in Fig. 5 of the drawings for distributing and admitting air to the interior of the fire pot and consequently it will be clearly understood that these air belts or chambers do not communicate with each 45 other, as the lower chamber and openings surrounding the fire pot draw the air down and through the wall of the fire pot, the upper chamber communicating with the interior thereof. The top section 27 of the fuel 50 magazine is mounted on this lower section, and is provided with a door 28 in the front thereof for charging the magazine, an opening 29 being formed in the top wall and communicating with a similar opening 30 55 formed in the radiator 31 which is positioned above it. This opening is adapted to be closed by means of the door or damper member 32 which is hinged to the radiator at the point 32^a, the lower end of the door 60 being connected to a rod member 33 which is adapted to be actuated by the opening and closing of the door 32, the free end of this rod 33 extends through the door proper and is adapted to butt against the member 65 34 which is pivotally connected at 35 to the

upstanding lug formed integral with the door. A handle 36 is pivotally mounted on the door and is formed similar to a bell crank, the upstanding leg 36^a being adapted to engage the latch 37, which is resiliently mounted in the member 34.

The lower end of the latch 37 is formed at an angle as shown, the upper end having a shoulder formed thereon, the end of which projects through the top of the offset portion of the member 34 which is recessed to receive it. A coiled spring 38 surrounds this reduced shank portion and normally tends to force the latch downwardly, a pin 39 limiting the downward movement.

When desiring to charge the fuel magazine, the handle 36 is turned to position as shown in dotted lines in Fig. 7, which forces the member 34 to position as shown in dotted lines, the weight of the damper 32 75 will force the rod 33 outwardly through the opening formed in the door, thereby opening the damper 32 and allowing the smoke and gases in the fuel magazine (should 80 there be any) to be drawn into the top radiator, thus smoke and gas does not escape from the furnace. After the door is opened the member 34 naturally swings back to original position, closing the opening in the door, and when the door is closed the end of the rod 33 butts against the member 34 and closes the damper 32, the end of the leg 36^a 85 forces the latch upwardly and again returns to its original position, the backward swing of the member 34 being limited by the stop 40 which is cast integral with the door.

The radiator proper is formed in two sections, the lower section being mounted on the hot air ducts 10, 10^a and 10^b, and the front of the furnace, while the top half is bolted to the lower section in the usual manner. A door 41 is provided in the front of this radiator to facilitate the cleaning thereof, and a damper 42 is hingedly mounted on the top of the rear hot air duct 10 and when in the position shown in full lines in Fig. 2 closes communication with the radiator or chimney, but when in the position as shown in dotted lines in the same figure, communication is established between this duct and the chimney, while the communication between the radiator and the chimney is closed. A post 43 is riveted to this damper and an operating rod 44 is connected thereto and extends to the front of the furnace, the end of the rod being bent at right angles to form a handle so that it can be operated when desired. The radiator is formed as clearly shown in Fig. 3 of the drawings, the two side ducts being inclined as shown and the radiator being formed with the forked extensions into which these ducts discharge, the rear duct is substantially vertical and a damper is provided as before explained.

The shape of this radiator makes it very easy to clean, as the cleaning instrument can be easily inserted and there are no corners or sharp curves to contend with, further, when cleaning the radiator the damper 42 is raised to the position as shown in dotted lines in Fig. 2, consequently closing the communication between the radiator and the chimney flue, the draft will then be down the side hot air ducts and out through the rear duct, thus the fine dust which may accumulate in the radiator will be drawn down and will fall into the ash pit of the furnace.

In practice the magazine is filled with fuel through the door 28, air is admitted through the dampers 22 and 25, the air circulating in the chamber surrounding the fire pot, and the lower end of the magazine being preheated as it flows downwardly as shown by the arrows, mingling with the flames and assisting in the burning of the soot and gases given off by the burning fuel. As the fuel is above the grate, the flames must eat up and against the downward draft, the air striking the fuel causes it to coke, consequently all soot and gases must pass through the flames, the hot air thence circulates around the chamber 8 and thence up the hot air ducts or flues 10^a and 10^b into the radiator 31, and thence out of the chimney flue.

When the fuel in the magazine cokes, and hangs in the magazine or when the fuel has a high percentage of ash content, and the grate is not manipulated to remove the ashes, the fire may eat up and through the body of the fuel in the magazine, then smoke and gases may rise into the magazine and is drawn off by the passage 45 which communicates directly with the passage 10. When the damper 42 is closed, this smoke and gas is drawn down and into the combustion chamber where it is ignited, or when the damper is open it is discharged directly to the chimney flue, this however is provided as a precaution measure and is very seldom needed.

The usual casing 46 surrounds the furnace and air ducts (not shown) lead therefrom to the registers in the different sections of the house.

From the foregoing description it will be obvious that I have perfected a simple and efficient downdraft furnace which is very economical to operate and easy to install and regulate.

What I claim is:—

1. A hot air downdraft furnace comprising a base, a combustion chamber mounted thereon, means for closing communication between the combustion chamber and the base, a fire pot, an annular air chamber surrounding the fire pot and communicating with a plurality of spaced apart openings into the combustion chamber, a radiator

mounted above the first pot, and a plurality of vertically disposed air passages leading from the combustion chamber to the said radiator.

2. A hot air downdraft furnace comprising a base, a combustion chamber mounted thereon, means normally held closed for establishing communication between the base and the combustion chamber, a fire pot, and a fuel magazine thereon, means surrounding the fire pot for pre-heating the incoming air fed to the grate, a radiator above the fuel magazine and hot air ducts connecting the combustion chamber and the radiator, an opening in the magazine adapted to communicate with a similar opening in the radiator, a door forming a closure therefor, and means on the door of the fuel magazine for automatically establishing communication between the fuel magazine and the radiator prior to and when the fuel door is operated.

3. A hot air downdraft furnace comprising a base, a combustion chamber centrally located above and communicating therewith, a fire pot mounted on the combustion chamber, and means surrounding said fire pot for preheating the inrushing air, a fuel magazine on the fire pot, a radiator above the magazine, hot air passages connecting the combustion chamber with the radiator, a passage between the magazine and the radiator, and means mounted on the fuel magazine door for automatically establishing and closing communication between the radiator and the said fuel magazine when the door is opened and closed.

4. A hot air downdraft furnace comprising a base, and a combustion chamber mounted thereon, manually operable means for controlling communication therebetween, a fire pot mounted on the combustion chamber, and a fuel magazine mounted thereon, means surrounding the fire pot and the lower end of the combustion chamber for pre-heating the air fed to the grate and the fire pot, a radiator above the fuel magazine, an air passage between the combustion chamber and the said radiator, and means mounted on the magazine door for automatically establishing or closing communication between the fuel magazine and the radiator when the door is opened and closed.

5. A hot air downdraft furnace comprising a base, a combustion chamber mounted thereon and communicating therewith, a series of overlapping dampers for closing communication between the combustion chamber and the base, a fire pot, and a fuel magazine mounted thereon, pre-heating chambers surrounding said fire pot and magazine, a radiator above the fuel magazine, and air passages connecting the combustion chamber with the radiator, an air passage between the magazine and the radi-

ator, a damper mounted in and adapted to close said opening, and means mounted on the magazine door for automatically opening said damper when the handle is operated, and closing said damper when the said door is closed.

6. A hot air downdraft furnace comprising a base, a combustion chamber mounted thereon, a grate mounted therein, a fire pot mounted on the said combustion chamber and a fuel magazine thereon, a chamber surrounding the fire pot for pre-heating incoming air, and a plurality of openings communicating with the said chamber for discharging the pre-heated air to the combustion chamber, a second air chamber surrounding the lower end of the fuel magazine and adapted to communicate with the interior of the fire pot, a radiator above the magazine, and passages between the combustion chamber and the said radiator, and a passage between the radiator and the magazine adapted to be automatically opened and closed when the magazine door is operated.

7. A hot air downdraft furnace comprising a base, a combustion chamber mounted thereon, a series of overlapping dampers therebetween, a grate, a fire pot, and a fuel magazine mounted thereon, an air chamber surrounding the fire pot for pre-heating the air, and a plurality of vertically disposed spaced apart openings for discharging the pre-heated air into the combustion chamber, a second air chamber surrounding the lower end of the magazine and adapted to communicate with the interior of the fire pot, means for breaking the current of air entering the chamber, a radiator above the magazine, and vertical passages spaced from the magazine for connecting the combustion

chamber therewith, a passage between the magazine and the radiator, a damper therein, and means mounted on the magazine door for opening and closing said damper when the magazine is operated.

8. A hot air downdraft furnace comprising a base, a combustion chamber mounted thereon, a fire pot above the said chamber, and air chambers for pre-heating the air admitted to the interior of the fire pot and the combustion chamber, a fuel magazine on the fire pot, and a radiator above the said magazine and adapted to communicate therewith, means for automatically opening and closing said means, vertical rearwardly inclined passages for connecting the combustion chamber to the radiator, and a rear air passage having a damper therein normally closed, and adapted when opened to have direct communication with the chimney flue to reverse the direction of the air in the other passages.

9. A hot air downdraft furnace comprising a base, a combustion chamber mounted thereon and communicating therewith, a fire pot and a fuel magazine mounted thereon, air chambers surrounding said fire pot, and fuel magazine for pre-heating the inrushing air, a radiator above the magazine adapted to communicate therewith when the magazine door is actuated, vertical air passages for connecting the combustion chamber and the radiator, a rear air passage having a damper therein and adapted to communicate directly with the chimney flue, and a passage between the fuel magazine and the said rear air passage.

In testimony whereof I affix my signature.

GEORGE A. MACKENZIE.
